SEBASTIAN ZIANI DE FERRANTI AND JOHN TURNER, OF HOLLINWOOD, ENGLAND, AS
SIGNORS TO FERRANTI INC., OF NEW YORK, N. Y.

RADIATOR OR COOLER

Application filed May 2, 1929, Serial No. 359,910, and in Great Britain July 3, 1928.

This invention relates to radiators or coolers more particularly for use in connection with oil immersed electric transformers.

The invention has for its object to provide improved constructions of radiators or coolers particularly from the point of view of ease of manufacture and erection and efficiency of air circulation.

The invention is particularly applicable in connection with constructions in accordance with the British specification No. 28154/27 (Patent No. 299,998).

The invention consists in a radiator or cooler unit comprising a plurality of tubes constructed from welded sheet metal, each tube being joined to its neighbour by a tubular distance piece.

The invention consists in a radiator or cooler unit comprising a plurality of tubes constructed from welded sheet metal, each tube being provided with an externally or internally flanged tubular element preferably formed from the tube sheet for welding, brazing or otherwise joining each tube to its neighbour.

The invention also consists in a radiator or cooler unit as set forth above, mounted upon a supporting arm furnished with a plurality of longitudinal ribs which impart rigidity with introduction of a minimum of constriction to flow of cooling medium.

The invention also consists in a radiator or cooler unit as set forth above wherein said arm is formed of bent sheet metal elements riveted, screwed or welded together.

The invention also consists in a radiator or cooler unit as set forth above, including a tube traversing the distance pieces or flanged portions and constituting a stiffener and a support for the unit, and the means of attachment of the unit to the appliance to be cooled.

The invention also consists in a radiator or cooler unit as set forth above, wherein the tubes are fashioned in such a manner as to permit direct and easy welding, either internally or externally, to provide integral passages of sufficient area to effect uniform distribution of the heating or cooling fluid to the various elements of the radiator unit

without the use of a header or separate collecting chamber.

The invention also consists in radiators or coolers substantially as hereinafter described.

Referring to the accompanying diagrammatic drawings:

Figure 1 illustrates a vertical cross-sectional view of a convenient construction in accordance with the present invention.

Figure 2 is a front view of one of the elements thereof.

Figure 3 is an enlarged vertical cross-sectional view of a detail.

Figure 4 is a front view of a modified construction.

Figure 5 is a vertical cross-section on the line A—A of Figure 4.

Figure 6 is a further enlarged fragmental plan view thereof.

Figures 7 and 8 are diagrammatic views illustrative of modified methods of construction, and

Figure 9 is a cross-sectional view of a modified form of supporting member for the radiator or cooler units.

In carrying the invention into effect in one convenient form by way of example as illustrated in Figures 1 to 3, we provide a plurality of flat tubes *a*, each of which is formed by pressing from sheet and by welding at the joint or joints. The flat sides of the tube are formed with lateral stiffening ribs *b* by pressing out the sheets and the two flat sides of each tube are spot welded together at intervals at *c* throughout their length, the points where the spot welding is effected lying conveniently between pairs of adjacent lateral stiffening portions.

Near the end of each tube a tubular depression *d* with internal flange *e* of a shape suited for easy welding is formed so that when joined thereby a fluid-tight structure resembling somewhat a concertina results.

The flanges may be external as indicated at *f* in Figure 9 if desired.

The orifices at the points of attachment of adjacent tubular members *d* may be circular as shown or of any desired shape.

In order to mount and support a unit

formed of such elements we insert through the tubular members *d* at each end a length of tubing *g* furnished with or without a flange for attachment to the transformer casing *m* (or other apparatus to which the cooler is to be applied). This tube is slotted at intervals so that a substantially uniform circulation of cooling liquid through the various parts of the unit is assured and the upper tube of each pair is furnished with a flanged member *i*. Two flanged tube elements *j* are rigidly attached to the supporting tubes by welding, and end caps are fitted to the end of the supporting tubes remote from the tank.

The end of the lower tube *g* of each pair is adapted to be drawn against a seating in a member *k* welded to the casing *m*.

In some cases we provide tubular distance pieces *o* which are internally flanged for example as illustrated in Figure 8 and attached to the tube sheets, e. g. by welding the flanges to the sheets.

Again in some cases we provide arms of angle section having longitudinal ribs upon which the radiator elements rest without constricting to any appreciable extent the free circulation of cooling medium. Conveniently such arms may be constructed of three sheet elements *n* (Figure 9) which may be spot or roller welded, screwed or riveted together to yield an extremely simple yet strong structure imposing a minimum of circulation restriction.

It will be appreciated that by these constructions enhanced freedom of circulation of air is also provided since the distance pieces (e. g. *d* Figure 3 or *o* Figure 8) and pressed-out or pressed-in flanges, united by welding, may be of considerably smaller external dimension than the width of the radiator tubes.

According to a modification in which instead of arranging the radiator units radially to the tank as in the example described with reference to Figures 1, 2 and 3 they are arranged tangentially as illustrated in Figures 4 to 6 we provide a T-piece *p* connected to the tank from which supporting tubes *g* or ribbed arms extend both ways for carrying and conveying circulating fluid to sets of radiator tubes formed as above and attached in the like manner to each other and to the supporting tubes.

The spot welding at *c* between the two sides of each flattened tube *a* may be performed between every lateral stiffening portion *b*, between alternate lateral stiffening portions, or just as desired in order to impart the required stiffness.

The examples described above are particularly applicable in connection with constructions according to British specification No. 28154/27 (Patent No. 299,998), but the invention may be applied in a variety of ways

other than in connection with the cooling of electric transformers.

Having now described our invention, what we claim as new and desire to secure by Letters Patent is:—

1. A heat exchanger comprising a plurality of tube elements constructed of welded sheet metal mounted upon a separate hollow rigid supporting member, a distance piece separating each pair of elements, a surface on each element welded to an abutting parallel surface on the adjoining distance piece.

2. A heat exchanger as claimed in claim 1, wherein said separate hollow rigid supporting member comprises bent sheet metal elements rigidly secured together.

3. A heat exchanger as claimed in claim 1, wherein said separate hollow rigid supporting member comprises a perforated tube substantially as described.

In testimony whereof we have signed our names to this specification.

SEBASTIAN ZIANI DE FERRANTI.
JOHN TURNER.
